UNITED STATES PATENT OFFICE.

IRA S. FISHER, OF MOLINO, MISSOURI.

CONCRETE TIE.

1,240,039.

Specification of Letters Patent. Patented Sept. 11, 1917.

Application filed December 29, 1916. Serial No. 139,487.

To all whom it may concern:

Be it known that I, IRA S. FISHER, a citizen of the United States, residing at Molino, in the county of Audrain and State of Missouri, have invented certain new and useful Improvements in Concrete Ties; and I do hereby declare the following to be a full, clear, and exact description of the invention, such as will enable others skilled in the art 10 to which it appertains to make and use the same.

The primary object of this invention is to improve the general constructions of concrete rail ties, by providing a tie of this 15 nature with a novel and effective reinforcement that will admit of the tie withstanding considerable weight without danger of the body of the tie becoming cracked, thereby increasing the life of the tie.

20 Another object of the invention is the provision of novel means for retaining the rails of the track on the tie.

Other objects will appear and be better understood from that embodiment of my 25 invention of which the following is a specification, reference being had to the accompanying drawings forming a part thereof, in which:

Figure 1 is a longitudinal sectional view 30 taken through the tie constructed in accordance with my invention, and showing the manner of securing the companion rails of a track to the tie, the said rails being in section,

Fig. 2 is a top plan view of the tie shown in Fig. 1,

Fig. 3 is an end view of a plurality of adjacent ties,

Fig. 4 is a transverse section taken through 40 one of the ties,

Fig. 5 is a perspective view of one of the rail-supporting plates detached from operative position,

Fig. 6 is a detail perspective view of one 45 end of the reinforcing element for the tie,

Fig. 7 is a perspective view of one of the innermost rail clamping plates detached from operative position.

Referring to the drawings in detail, the 50 rail tie is shown as consisting of a body portion 1 formed of concrete. Embedded within the concrete body 1 of the tie is a rein-

forcing element 2 that consists of an elongated and flat plate, having its opposite longitudinal edges bent laterally in opposite 55 directions, as shown at 3, and thence bent upon themselves, in opposite directions and in parallelism with the laterally bent portions 3 to provide flanges 4 that project beyond the plate 2, as shown in Fig 6 of the 60 drawings. By so bending the opposite longitudinal edges of the plate 2, a reinforcing element of I shape in cross section will be provided. The plate 2 is provided with a plurality of openings 5, that admit of the 65 material, of which the body 1 of the tie is formed, entering therein and securely anchoring the plate 2 in position and also admit of a greater compactness of the concrete. The flanges 4 are provided with inwardly 70 extending tongues 6, which are embedded within the concrete and are formed by displacing portions of the flanges 4, and the openings defined by the displacement of the tongues 6 form pockets for the reception of 75 portions of the concrete forming the body 1 of the tie. The flanges 3 and 4 on the plate 2 are reduced, adjacent their opposite ends, as shown at 8, for a purpose to be hereinafter described.

80 A pair of rail-supporting plates 9 are mounted on the upper surface of the tie 1 and are located, respectively, adjacent the opposite ends of the tie, and are adapted to support the companion rails A of a track. 85 Each of the plates 9 is of substantially rectangular shape and has its opposite ends provided with raised portions 10 and 11, the raised portion 11 being disposed innermost and has its inner longitudinal edge 90 beveled, as shown at 12. Each plate 9 has associated therewith a pair of clamping plates designated, respectively, by the numerals 13 and 14 and are located, respectively, on opposite-sides of the adjacent rail 95 A. The plate 13 is located exteriorly of the adjacent rail A and has its outer edge abutting against the adjacent edge of the raised portion 10 on the plate 9, and the plate 14 abuts against the raised portion 11 on the 100 inner end of the plate 9 and has that edge opposing the beveled face 12 beveled to agree with the beveled face 12, as shown more particularly in Fig. 2 of the drawings. The

plate 9 is provided adjacent the raised portion 11 with a corrugated surface 15, which is adapted to coöperate with a similar corrugated face formed on the lower or under 5 side of the plate 14, so as to prevent lateral movement of the plate 14 when the latter is in operative position. The plates 13 and 14 are provided with flanges 16 which engage over the adjacent longitudinal edges of the 10 base flange of the adjacent rail A.

A pair of transversely extending and spaced plates 17 are embedded in the body 1 of the tie, at each end thereof, and are located beneath the plate 2, and adjacent the 15 lower side of the body of the tie 1, and underlie the respective reduced portions 8. The plates 17 of each pair are so spaced from each other that they underlie the upper adjacent rail fastening plates 13 and 14. Each 20 plate 17 of each pair is provided with a pair of spaced openings through which extend a pair of bolts 18. All of the bolts 18 have their lower ends provided with heads that are disposed adjacent the lower 25 side of the tie 1 and embedded therein. The bolts 18 extend through openings 19 formed in the plates 9 and through openings 18^a formed in the respective rail-fastening plates 13 and 14 and have their upper ends 30 threaded for the reception of suitable lock nuts 20. The openings 18^a in the innermost plates 14 that receive the upper ends of the bolts 18 are elongated and extend in parallelism with the beveled faces on the 35 innermost raised portions 11 and the plates 14. By locating the lower or headed ends of the bolts 18 adjacent the lower side of the body of the tie 1, removal of the bolts 40 can be easily and conveniently effected, it necessitating only the removal of the nuts 20 and then striking the upper end of the bolts 18 with a suitable implement, such as a hammer, so as to force the bolts 18 downwardly and causing the heads or lower ends 45 thereof to displace the concrete located beneath the same, so that the headed ends of the bolts will be exposed. After the bolts have been withdrawn new bolts can be substituted therefor and the openings made in 50 the lower side of the tie by the displacement of the material on the downward movement of the bolts, can be filled with concrete so as to conceal the lower ends of the bolts 18, and also to help support the bolts in position. The bolts 18 extend through the recesses formed by the reduced portions 8, so that the bolts can lie in close proximity to the plate 2.

The operation of securing the rails in position on the tie is effected as follows: The rails are first positioned on the plates 9, approximately centrally thereof, and plates 13 are then disposed at the outer sides of the rails and secured to the plates 9 by the outer- 65 most pairs of bolts and nuts 18 and 20, the

flanges 16 on the outer plates 13 engaging over the outer longitudinal edges of the base flanges of the rails. The innermost plates 14 are then positioned at the inner sides of the rails with the elongated openings there- 70 in receiving the upper ends of the innermost pairs of bolts 18, each of the plates 14 being held by a suitable tool, not shown, in spaced relation with the adjacent plate 9 so as to hold the corrugated lower surfaces of the 75 plates 14 spaced above the adjacent corrugated surfaces 15 on the plates 9. Each plate 14 is then moved transversely of the adjacent plate 9, in either direction, resulting in the beveled faces on the plate 14 and 80 the adjacent raised portion 11, and also the walls of the elongated slots in the plate 14, effecting movement of the plate 14 either toward or away from the adjacent rail. When the plates 14 have been given the re- 85 quired amount of movement either toward or away from the rails, the said plates are lowered so as to effect engagement between the corrugated surfaces formed, respectively, on the lower sides of the plates 14 and the 90 upper sides of the plates 9, so that the plates 14 will be held against lateral movement on the plates 9. The nuts 20 on the innermost pairs of bolts 18 are then adjusted against the plates 14, so as to prevent upward move- 95 ment of the plates 14.

It is evident that various changes might be resorted to in the construction, form and arrangement of the several parts without departing from the spirit and scope of the invention as claimed. 100

Having thus described my invention what I claim as new, is:

1. A rail tie comprising a body portion formed of concrete, an elongated metallic plate embedded within the body and having its opposite longitudinal edges bent in opposite directions and then bent upon themselves in reverse directions, the said bent edges providing flanges, the said flanges 105 being reduced in width adjacent the opposite ends of the plates, and tongues formed on the flanges and engaging in the tie body. 110

2. A rail tie comprising a body portion formed of concrete, an elongated metallic plate embedded within the body and having flanges formed on the longitudinal edges thereof, the said flanges being reduced adjacent the opposite ends of the plate to provide recesses, rail-supporting plates located 115 on the upper side of the tie body and having openings therein, and bolts extending through the tie and through the recesses formed by the reduced portions of the flanges and through the openings in the supporting 120 plate. 125

3. A rail tie comprising a body portion formed of concrete, an elongated metallic plate embedded within the body of the tie, plates located below the first-mentioned 130

plate and having openings therein, rail-supporting plates located on the upper side of the tie body, and bolts extending through the openings in the second-mentioned plates and through the tie body and having their lower ends disposed wholly within the tie body and having their upper ends extending

through the openings in the rail-supporting plates.

IRA S. FISHER.
